(57) **CLAIM**

I claim the ornamental design for an orientation band for hard hats, as shown and described.

DESCRIPTION

FIG. 1 is a perspective view of an orientation band for hard hats;

FIG. 2 is an isometric view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

The broken line showing is for environmental purposes only and forms no part of the claimed design.
